UNITED STATES PATENT OFFICE.

GUSTAV A. BOETTCHER, OF JERSEY CITY, NEW JERSEY.

QUILTING-MACHINE.

1,218,517.

Specification of Letters Patent.

Patented Mar. 6, 1917.

Application filed November 10, 1913. Serial No. 800,178.

To all whom it may concern:

Be it known that I, GUSTAV A. BOETTCHER, a subject of the Emperor of Germany, residing at Jersey City, in the county of Hudson and State of New Jersey, have invented certain new and useful Improvements in Quilting-Machines, of which the following is a specification.

This invention appertains to what I term multi-needle sewing machines, particularly to the type of these machines designed primarily for the quilting of goods. As a general thing, machines of this class embody a well known organization of mechanisms including the needle bar mechanism, feed motion for the goods, shuttle and shuttle drive instrumentalities, tension and take-up mechanisms, etc.

I have devised an especially compact and efficient operating mechanism for the needle bar and presser foot devices which are thus rendered certain in action and are susceptible of ready adjustment by the provision of suitable means for the purpose.

In addition to the foregoing, an extremely important feature of my invention resides in the peculiar take-up mechanism which I utilize in conjunction with the needle bar mechanism, the former being operable by the latter and affording a very desirable means for regulating the supply of thread for the formation of the loops and producing the necessary tension of the stitches in sewing goods of different thicknesses, or using stitches of different lengths.

Other detail features of the invention for which novelty will be ultimately claimed are presented more fully in the following description, along with the details of the mechanism hereinbefore referred to.

In the accompanying drawings:—

Figure 1 is a front view of a machine embodying the essential features of the invention.

Fig. 2 is a top plan view of the same.

Fig. 3 is a vertical, sectional view.

Fig. 4 is a side view showing the carriage forming a part of the feed motion and bringing out clearly the manner in which forward motion is transmitted intermittently to the feed rolls.

Fig. 5 is an enlarged section bringing out more clearly the shuttle driving mechanism as seen in Fig. 3.

Figs. 6 and 7 are front and top plan views, respectively, disclosing the shuttle

movement and the peculiar form of the shuttle races.

Fig. 8 is a view of a modification of the shuttle drive means.

Fig. 9 is a detail view bringing out more clearly the operative connections intermediate the crank wheels and the shuttle carriers.

Fig. 10 is a fragmentary view of one of the thread guide bars showing the peculiar form of the guiding eye or bushing.

In the drawings A denotes the bed or base of the machine which will be supported upon suitable supporting legs or equivalent means, as customary, and upon which the various mechanisms now to be set forth in detail are carried. Spaced apart and secured in any substantial way to the base A

are side frames B, and between said frames B are located the needle bar, presser foot, and take-up mechanisms, along with co-operating instrumentalities. The frames or members B are connected together rigidly by means of large cross bars 1 located one

above the other, and a small cross bar 2. The cross bars 1 support a plurality of guide brackets 3, the latter merely having suitable openings through which the cross bars pass, and being held at proper adjustments in the length of the cross bars by means of set screws or the like. The brackets 3 are designed to act as guiding means

for the vertical guide rods 4 of the needle bar 5, the latter being provided with a large number of needles as required in a machine of this special type. Certain of the brackets 3 also form guiding means for guide bars 6 to the lower ends of which is secured the presser foot 7 which consists of a flat

plate or bar of practically the same length as the needle bar 5, located beneath the needle bar and having apertures through which the various needles 5^a operate. A rock shaft 9 is mounted in suitable bearings

on the frames B and said rock shaft is operatively connected with the main drive shaft 10 through the medium of the connecting rod 11 and eccentric 12, the latter carried by said shaft 10. Any suitable driving

connection may be established, however, between the shafts 9 and 10, this being immaterial to the invention. Suitable arms 13 are carried by the shaft 9 and connected by

links 14 with adjustable blocks 15 secured to the needle bar guide rods 4, motion being communicated through the medium of the

above parts from the shaft 9 to the needle bar 5. The presser foot 7 is reciprocated vertically as well as the needle bar 5, by motion transmitted from the shaft 9. For 5 this purpose the shaft 9 has eccentrics 16 thereon which engage rollers 17 carried by arms 18 attached adjustably to the upper ends of the guide bars 6. Springs 19 encircle the bars 6 and are connected at one end 10 to the bars to normally tend to force the presser foot 7 downwardly into engagement with the goods.

From the foregoing it will be understood that in the operation of the machine the 15 needle bar 5 and the presser foot 7 are each reciprocated vertically at comparatively high speed through the operative connections of these parts with the main shaft 10.

The goods to be sewed together are fed 20 from suitable rolls (not shown) mounted on the carriage D, over a cloth plate E, (see Figs. 1 and 3) beneath the needle bar 5 and presser foot 7 respectively, from thence upward between the feed rolls 20 which are 25 mounted on the carriage D, and from said feed rolls the goods in quilted or stitched condition is reeled about a suitable roll, not shown, but carried by the upper ends of arms 21 which project upwardly from the 30 frames B, being attached to the latter by suitable means.

The feed movement will now be described. Referring particularly to Figs. 1, 3 and 4 it will be observed that the carriage D is supported upon rollers 22 in the usual way, and any suitable means is employed for imparting lateral back and forth movement to the carriage in the well known manner. Since the means just mentioned forms no part of 40 this invention the same will not be described. The mechanism for imparting forward feeding movement to the goods being sewed comprises the feed rolls 20 before mentioned, same being mounted in suitable 45 bearings upon extensions 23 of the sides of the carriage D. The rollers 20 are driven from the main shaft 10 by peculiar means including a stub shaft 24, (see Fig. 4) having a bevel gear 25 at one end meshing with 50 a corresponding gear 26 on said shaft 10. The stub shaft 24 is connected by a universal joint 27 and extensible shaft 28 with a worm 29 that engages a worm gear 30 connected with the end of one of the rolls 55 20. The sections of the shaft 28 are connected by a feather and spline or equivalent means, and said shaft obviously maintains a driving connection between the shaft 10 and worm 29, notwithstanding the variation 60 in the position of the carriage D relative to the shaft 24, caused by the back and forth lateral movement of the carriage. The worm 29 has the threads thereof pitched at a predetermined angle with respect to the 65 axis of the worm, except at certain points

where said threads are practically straight or extended a short distance at a right angle to the axis of said member. These portions of the worm threads, namely those unprovided with the normal pitch necessary for 70 causing a feed movement of the worm wheel 30, engage the wheel 30, and the feed or rotating movement of the latter will be discontinued momentarily while at all other times a positive movement will be imparted 75 to the feed rolls through the worm 29. It will of course be understood that the feed rolls are intergeared, the meshing gears connecting the same being indicated 31 and being located at the ends of the rolls 20 adjacent to the mechanism for moving the carriage laterally. The means employed for operating the rolls 20 is positive in its action, not being dependent upon any devices uncertain in action, such as springs, etc., 80 which in the event of failure to work properly will spoil the pattern of the goods entirely, as will be readily apparent.

Between the frames B are short vertical standards 32 which carry a pair of transverse supporting bars 33. These parts are included in the shuttle mechanism in that they carry the shuttle races 34 which are secured directly by suitable fastenings at opposite ends, to the bars 33 aforesaid. Not 95 only do the bars 33 support the shuttle races 34 but the said bars are utilized as guides for the drive rods 35 which connect the shuttle carriers 36 with the shuttle driving means proper. There is, of course, provided for each needle 5^a of the needle bar 5, a shuttle and shuttle carrier. All of the carriers 36, however, are secured to a transverse plate 37 which is seated in recesses of blocks 38 attached to the rear ends of the 100 drive rods 35. The front ends of the drive rods are connected together by a plate 39 near the opposite ends of which are provided slots, and blocks 40 are slidable lengthwise of said slots and are engaged by crank 110 pins 41 of crank wheels 42, two of which are utilized preferably for driving the shuttle mechanism. The crank wheels 42, (see Fig. 5) are carried by the upper ends of shafts 43 mounted in incasing standards 115 44 located beneath the cloth plate E. Suitable bearings are provided in the standards 44, for the shafts 43 and these bearings are protected from entrance of dust or foreign matter by means of packing shown at 45. 120 Intermediate its ends each of the vertical shafts 43 has a worm gear 46 secured thereto in engagement with a worm wheel 47 mounted on the main shaft 10. The crank wheels 46 are therefore driven direct from 125 the shaft 10, the rotary movement of the wheels 42 being utilized to reciprocate the members 35 and the shuttle carriers 36, in a manner readily apparent.

If desired the alternative shuttle driving 130

means shown in Fig. 8 may be employed, the crank wheel 42' as shown in this figure being carried by a short shaft 43' on which is mounted a bevel gear 46'. The gear 46' 5 meshes with a gear 47' mounted on the main shaft 10. Practically the only difference between the preferred and alternative driving instrumentalities resides in the fact that bevel gearing is substituted for worm gear-
10 ing.

As hereinbefore referred to, the shuttle races 34 are peculiarly constructed. Each race is provided with the usual flat side and the opposite curved side or race-way 34'. 15 A needle groove 48 is provided in the flat side of the race 34 and the shuttle 49 is of the embroidery machine type, not having any external springs or thread guides and not necessitating the employment of a bobbin. In order that this shuttle may be used without likelihood of entanglement of the thread owing to its becoming clamped between the race and the needle plate, the upper edge of the race 34 is cut away as shown at 20 34" to provide a clearance space for the thread as the shuttle works back and forth in moving through the loop of thread, and the manner in which the thread feeding from the shuttle is free to move in the 25 clearance space 34" will be quite clear on reference to Figs. 6 and 7 of the drawings. It is understood that such clearance may also be made in any other way, without departing from the spirit of the invention.

35 Passing now to one of the most important features of the invention, the take-up mechanism hereinbefore referred to is shown clearly in Figs. 1, 2 and 3 of the drawings. This mechanism comprises the take-up bar 40 50 having suitable thread openings or eyes therein carried by the front ends of a pair of levers 51. The levers 51 are provided at their rear ends with slots 51' in which operate blocks 52 that are carried by pins or 45 studs on arms 53 attached to the cross bar 2 intermediate the frames B. The levers 51 are virtually fulcrumed, therefore, upon the arms 53 of the cross bar 2 and intermediate their ends said levers are connected 50 by pins or studs 54 with blocks 55 secured to the upper ends of the needle bar guide rods 4. It will thus be evident that, assuming that the threads extending to the needles 7 are passed through the eyes or openings 55 of the take-up bar 50, said threads will be subjected to the action of said bar as the latter is raised and lowered, owing to the movement imparted thereto by the needle bar guide rods 4. The supply of the thread 60 for the formation of the loops through which the shuttles pass in forming a lock stitch may be nicely regulated through the use of the take-up mechanism above set forth, due to the fact that the bar 2 which 65 supports the arms 53, is adapted to be ro-

tatably adjusted so as to vary the leverage of the members 51, movement of the arms 53 changing the fulcrum point of the levers 51 in an obvious way. The rotative adjustment of the bar 2 is obtained by means of 70 nuts on the ends of said bar. The tension of the stitches in sewing goods of different thicknesses, and the production of stitches of different lengths, is also susceptible of nice control owing to the adjustability of the 75 take-up mechanism as just set forth.

The side frames B carry vertical bars 56 to the upper extremities of which is secured a transverse bar 57 that carries pins or other suitable supports 58 for spools or reels 59 80 of thread. From the spools 59 the thread feeds downwardly through guide holes or eyes 60 in the tension bar 61, said tension bar being connected at its ends with the bars 56 above referred to. The tension bar 56 is 85 equipped with tension devices 62 of any conventional type and the thread passes from the guide holes 60 over an adjacent disk tension device and from thence passes downward through guide holes or eyes of still 90 another guide bar 63 located near the lower ends of the bars 56 and also supported by the latter. After passing through the guide holes of the bar 63 the thread is extended upwardly through the guide holes or eyes of 95 the take-up bar 50, after which the thread passes downwardly to the needles 5a. As the needle bar 5 moves upward with its guide rods 4 the take-up bar 50 will be raised correspondingly, owing to rocking 100 movement imparted to the levers 51, the loop of thread through which the shuttle has just passed being tightened by this action. On the other hand, as the needle bar 5 and its needles move downward, the take-up bar 105 moves in a corresponding direction and supplies an abundance of slack thread for the formation of the loop through which a co-acting shuttle passes. Owing to the provision of the take-up bar 50, all of the 110 threads are tightened simultaneously and uniformly in producing the stitches. If desired a separate tension for each thread may be provided.

In sewing machines of the type hereinbefore described considerable difficulty has been experienced heretofore in providing thread guiding holes or eyes which do not cause breaking and splitting of the thread. It has heretofore been proposed to simply 115 form an opening in a bar or other part in order to provide a thread guiding hole and repeated repolishing of these openings is necessary to maintain the same in smooth condition such that splitting of the thread is 120 not caused. To avoid the above somewhat disadvantageous thread guiding means I contemplate the employment of porcelain or glass bushings which are fitted into openings of the part having the thread guiding 125 130

hole, and these bushings I find remain in good condition a much longer time than the common thread guiding holes or openings at present used. An especial advantage 5 incidental to the use of the porcelain or glass bushings, one of which is fully illustrated in Fig. 10 of the drawings, resides in the fact that when the bushing has become worn or rough it may be replaced in 10 a very short time.

It may be observed that the cross bars 1 on which the brackets 3 are mounted, and which connect the side frames B of the machine, are not only advantageously used because they afford supports for the parts 3, 15 but they allow the goods which is operated on to be seen at all times as it passes from the needle plate to the feeding rolls 20, the pattern which is being used in the quilting operation thus being in plain view of the operator. The brackets 3 may, of course, be finished in lots and are designed to be readily interchangeable in so far as their mounting upon the members 1 is concerned. 20 A highly desirable adjustment of the needle bar presser foot and associated parts, in relation to the shuttle races and needle plate, is afforded by the provision of the bars 1.

Having thus described the invention, what 30 is claimed as new is:—

1. In a quilting machine, the combination of a bed, side frames mounted thereon, cross bars connecting said frames together, a rock shaft mounted on said frames, brackets supported by said cross bars, a needle bar, a presser foot beneath the needle bar, needles on the needle bar adapted to operate through the presser foot, guide rods extending upwardly from the needle bar and from the 35 presser foot and mounted in the brackets 40 aforesaid, means intermediate the rock shaft and said needle bar and presser foot for reciprocating the latter parts in timed relation to each other, levers, a take-up bar carried by said levers, and connections whereby the motion of said rock shaft is imparted to said levers for operating the take-up bar.

2. In a quilting machine, the combination of a bed, side frames mounted thereon, cross 50 bars connecting said frames together, a rock shaft mounted on said frames, brackets supported by said cross bars, a needle bar, a presser foot beneath the needle bar, needles on the needle bar adapted to operate through the presser foot, guide rods extending upwardly from the needle bar and from the 55 presser foot and mounted in the brackets

aforesaid, means intermediate the rock shaft and said needle bar and presser foot for reciprocating the latter parts in timed relation to each other, levers, a take-up bar carried by said levers, and connections intermediate said levers and the needle bar guide rods whereby motion is imparted to the take-up 60 bar. 65

3. In a quilting machine, the combination of a bed, side frames mounted thereon, cross bars connecting said frames together, a rock shaft mounted on said frames, brackets supported by said cross bars, a needle bar, a presser foot beneath the needle bar, needles on the needle bar adapted to operate through the presser foot, guide rods extending upwardly from the needle bar and from the presser foot and mounted in the brackets 70 aforesaid, means intermediate the rock shaft and said needle bar and presser foot for reciprocating the latter parts in timed relation to each other, levers, a take-up bar carried by said levers, connections whereby the motion of said rock shaft is imparted to said 75 levers for operating the take-up bar, and adjustable fulcruming means for said levers enabling variation in the take-up action of the take-up bar. 80

4. In a quilting machine, the combination of a bed, side frames mounted thereon, cross bars connecting said frames together, a rock shaft mounted on said frames, brackets supported by said cross bars, a needle bar, a presser foot beneath the needle bar, needles on the needle bar adapted to operate through the presser foot, guide rods extending upwardly from the needle bar and from the presser foot and mounted in the brackets 90 aforesaid, means intermediate the rock shaft and said needle bar and presser foot for reciprocating the latter parts in timed relation to each other, levers, a take-up bar carried by said levers, connections whereby the motion of said rock shaft is imparted to said 95 levers for operating the take-up bar, another cross bar connecting the side frames, arms carried by said last mentioned cross bar and adjustable thereon, and fulcrums on 100 said arms engaging the levers and relatively movable in respect to the latter. 105

In testimony whereof I affix my signature in presence of two witnesses.

GUSTAV A. BOETTCHER.
